UNITED STATES PATENT OFFICE.

GERSHOM M. PETERS, OF CINCINNATI, OHIO.

RAILROAD-RAIL.

1,104,923.

Specification of Letters Patent. Patented July 28, 1914.

Application filed April 21, 1913. Serial No. 762,453.

To all whom it may concern:

Be it known that I, GERSHOM M. PETERS, a citizen of the United States, residing at Cincinnati, in the county of Hamilton and State of Ohio, have invented certain new and useful Improvements in Railroad-Rails, of which the following is a specification.

This invention pertains to a new and improved form of rail for use in connection with steam, electric or other cars.

The invention consists in substantially the construction, combination and arrangement of the several parts shown in the accompanying drawings and described in the specification, but more particularly pointed out in the appended claims.

In the drawings: Figure 1 is a cross-section of one form of the rail; Fig. 2 is a cross-section of a modified form of the same; Fig. 3 is a side elevation of a rail constructed in accordance with the principles of the invention, and Fig. 4 is a sectional plan view of a switch.

In the present railroad construction and in most of the exploited improvements thereto, it is customary to abut two solid rails and to fasten them together by means of side plates with bolts extending through the rails and side plates. The obvious disadvantage of this construction is that the joint of the rails cannot be kept smooth, and sooner or later the abutting edges of the rails become worn, causing a jar or jolt to be given to the car which runs over the rail, and also causing a disagreeable noise in so doing. The present invention contemplates a rail constructed of two parts, one within the other, and with the parts of

each rail so disposed that the joints of the interior and exterior members do not come at the same place. In other words, they are staggered with respect to each other so that there is no tendency of the combination rail to sag at one point more than another, or to wear at the abutting joints of either the interior or exterior rail more than at any other place. This produces a smooth, resilient and comparatively noiseless rail.

The preferred form of rail comprises an exterior member A, provided with the usual tread C, and formed with a central recess D from the base separating the web into two members E, which are divergent at their lower portion to form the extremities F at the base. An interior member B, which

may be of hollow shell construction, as shown in Fig. 1, or which may be a solid member B', as shown in Fig. 2, is adapted to fit the recess in the exterior rail A closely at all points so that it will be in actual contact with the inside surface of the recess. This interior member B or B' is also provided with the divergent base portions G or G', the lower faces of which are substantially in the same plane as the lower edges of the extremities F of the exterior member A.

The two rail members A and B are adapted to rest upon the ties H in the usual manner and are secured thereto by means of the spikes I or by any other well known fastening devices. Both the exterior rail member and the interior member are continuous in length and are arranged abutting each other in succession to form a continuous rail. The abutting points of the two rail members are preferably spaced apart, as shown more clearly in Fig. 3, in which the abutting point of the interior rail member is indicated by the character J, and the abutting point of the outer member is represented by the character K. With this construction, the outer rail members will always be supported by the inner rail member at their joint, and the inner rail members will always be supported and protected by the outer rail member at their joint. There is, therefore, no tendency of the rail to sag or to form an uneven joint at any of the abutting places, and the result is a continuous smooth rail which produces an even continuous track over which cars will ride smoothly and evenly and with minimum noise.

With this construction, it is obvious that no side plates or fastening bolts are necessary for securing the interior and exterior rail members together, for both of them are held firmly in position by means of the spikes or other fastening devices. This results in a more easily maintained construction, for there are no bolts requiring watching and tightening, and there is no extra cost for plates, bolts, or the boring of holes.

This construction does not interfere with the formation of switches, for the ends of the rails may be tapered to fit in under the overhanging tread of rail, but it is preferable to secure the tapered end of the interior and exterior members together in some suitable manner, as, for example, by means

of a rivet L, as indicated in Fig. 4. With this construction, the rail with the tapered end may be used to form a switch and there will be no danger that the tapered ends of the rails will be caught or bent by the flanges of the car wheels as they pass over the rails.

If desired, the interior and exterior rail members may be composed of different material; for example, the exterior rail member may be composed of steel, while the interior rail member may be made of wrought iron, or other suitable material. If made of wrought iron or other similar material, it is probably better to make the interior rail member of solid construction, as shown in Fig. 2. More resiliency, however, is provided in a rail constructed as shown in Fig. 1, and a relatively stronger rail may probably be produced with less metal; for the division of the web distributes the weight on the rail to better advantage and makes a wider sustaining support for the tread. Both rails put together in this form are not only more resilient, but will so strengthen and support each other as to prevent buckling and bending. The side thrust is also better provided for because brought against the strength of a double arch and a lean-to of upright.

In the accompanying drawings and in the foregoing description is set forth the preferred embodiment of my invention, but it is obvious that one skilled in the art may make modifications thereof without departing from the principle of the invention.

What I claim is:

1. A combination rail comprising an exterior casing formed with the usual tread and having its supporting sides curved exteriorly and interiorly with a gradually increasing curvature until it reaches the tie, and an interior supporting member fitting in a recess formed in the exterior casing and likewise having its side members curved to contact with the inner surface of the side members of the exterior casing until the lower ends of such interior supporting members likewise contact with the tie.
2. A combination rail comprising the usual solid tread and recessed below such tread in an increasing width of recess so as to form

curved side supporting members, and an interior supporting member likewise recessed and contacting on its outer surface with the inner surface of the side supporting members from the tread to the base of such outer casing.

3. A composite rail comprising an outer casing having the usual solid tread and interiorly recessed to form side supporting members extending with a gradually increasing divergent curvature to their base which rests on the tie, in combination with an interior supporting member fitting in such recess and having its side members follow on the curve of the side members of the casing both interiorly and exteriorly until it rests upon the tie, and means for fastening the base of the rail to the tie.

4. A composite rail comprising a solid tread and side wings curving downwardly therefrom with a gradually increasing curvature exteriorly and interiorly until they form a practically horizontal support on the tie, in combination with an interior supporting member fitting between the flanges of the exterior member and likewise having depending flanges the outer surfaces of which correspond to the inner surfaces of the outer casing and follow the outlines thereof to the tie and are provided with a gradually widening interior recess, and means for clamping the base of the rail to the tie.

5. A composite rail comprising an exterior casing having the usual solid tread and vertical supporting side webs formed on a divergent curve interiorly and exteriorly and leaving within a gradually widening recess, in combination with an interior supporting member of similarly curved exterior surface to the interior curved surface of the casing and having a widening interior recess and two members of the rail joint of such longitudinal sections as will break joint with each other.

In testimony whereof I have signed my name to this specification, in the presence of two subscribing witnesses, on this 17th day of April, A. D. 1913.

GERSHOM M. PETERS.
